J. REGAN.
BRICK,
FILED AUG. 31, 1920.

Inventor

Joseph Regan,

WITNESS:-
Chas. R. Griesbauer

By *Edward Regan*
his attorney

UNITED STATES PATENT OFFICE.

JOSEPH REGAN, OF ROCKVILLE, CONNECTICUT.

BRICK.

Application filed August 31, 1920. Serial No. 407,101.

To all whom it may concern:

Be it known that I, JOSEPH REGAN, a citizen of the United States, residing at Rockville, in the county of Tolland and State of Connecticut, have invented new and useful Improvements in Bricks, of which the following is a specification.

This invention relates to bricks for the construction of the walls of buildings and 10 the like, and the prime object of the invention is to enable the accurate spacing of the bricks as they are placed in the wall without requiring the skill of a trained brick layer.

In carrying out my invention I employ 15 spacing ribs, and it is an object of the invention to so dispose the ribs that no portions thereof appear at either face of the wall, whereby the wall has the appearance of having been constructed in the usual 20 manner. The spacing ribs are of course uniform in all of their dimensions in order that accurate spacing of the bricks may be accomplished by unskilled labor.

With these and other objects in view, the 25 present invention consists in the combination and arrangement of parts as will be hereinafter more fully described, illustrated in the accompanying drawings and particularly pointed out in the appended claims, it 30 of course being understood that changes in the form, proportion, size and minor details may be made, within the scope of the claims, without departing from the spirit or sacrificing any of the advantages of the invention.

The figure of the drawing is an inverted perspective view of a building brick embodying the features of the present invention.

40 The brick 1 may be formed of any suitable material and is in the form of a parallelepiped having six faces of the usual or of any preferred dimensions. On the bottom face of the brick 1 provide a plurality of 45 ribs 2 extending longitudinally of the brick and terminating short of opposite ends thereof, each end of each rib being beveled as indicated at 3. Each rib is rectangular in cross section and the several ribs are uniform in 50 every particular, the depth of each rib being equal to the spacing desired between adjacent bricks. One end of the brick is provided with a plurality of spacing ribs 4 having beveled ends 5 terminating 55 short of the top and bottom faces of the

brick, said ribs extending along the vertical dimension of the end of the brick.

In using a brick of the present invention in the construction of a wall, a suitable amount of mortar is put in place in the usual 60 way and then the brick is placed downwardly upon the mortar and tamped with a trowel or otherwise forced downwardly until the ribs 2 engage with the top surface of the underlying brick or foundation on which 65 the mortar has been placed whereby the newly placed brick will be accurately spaced without requiring the skill of a trained expert. By locating the ribs upon the bottom of the brick, the top of the brick is smooth 70 and unobstructed and affords a flat surface against which the trowel may be struck in tamping or forcing the brick into place. The ribs 4 on the end of the brick of course 75 accurately space the end of the brick from the adjacent end of the last laid brick in the same course. Inasmuch as I employ spacing means on one end only of the brick, the tamping of the brick on its opposite end 80 may be accomplished in the usual manner. By placing the spacing ribs on the bottom and on one end only of the brick, the ribs are not struck by the trowel when tamping the brick in place, and consequently damage to the ribs when laying the brick is not 85 liable to occur. When the brick has thus been set in place, all of the ribs will be embedded in the mortar thereby serving to provide an extremely strong bond between the 90 brick and the mortar and effectually preventing lateral accidental displacement of the brick before the mortar hardens, and also anchors the brick in place in the hardened mortar. In as much as the ribs are located inwardly from the front and rear upright faces of the brick, said ribs are concealed by the mortar and the wall has the appearance of having been built in the usual 95 way by skilled brick layers.

When a brick of the present invention is 100 laid with one end at the outer face of the wall, the ends of the ribs 2 are concealed by the mortar, and of course it is the plain end, rather than the ribbed end, which is located at the outer face of the wall.

The beveled ends of the ribs serve to permit the easy sinking of the ribs into the mortar.

If it should be desired to dispense with the ribs, they can be readily broken off by 110

the use of a trowel, so that the brick can be conveniently converted into an ordinary brick without materially marring the appearance of the brick.

5 Each of the ribs is provided with a broad outer bearing face so as to give a substantial bearing against the adjacent brick, and also to give each rib sufficient bulk to prevent chipping and breaking thereof during 10 transportation and handling.

By having each of the ribs 2 continuous, the brick may be broken transversely for use where a short portion of brick is desired, and as said ribs 2 are continuous, the portion 15 of the brick to be used will have continuous rib portions 2 and therefore the brick portion may be placed accurately upon the next below brick.

What I claim is:

1. A building brick of rectangular form 20 having six flat faces, the bottom face being provided with a plurality of substantially parallel ribs extending longitudinally of the brick, terminating short of opposite ends thereof and extending equally at opposite 25 sides of the transverse middle of the brick.

2. A building brick of rectangular form having six flat faces, the bottom face being provided with a plurality of substantially parallel ribs extending longitudinally of the 30 brick, terminating short of opposite ends thereof and extending equally at opposite sides of the transverse middle of the brick, each rib having a continuous flat outer bearing face and beveled opposite ends.

JOSEPH REGAN.
